ORNAMENTAL HAIR CLAMP

Daniel A. Triangolo, Cranston, R.I., assignor to Danal Jewelry Company, Providence, R.I., a corporation of Rhode Island

Filed Aug. 13, 1962, Ser. No. 216,395

6 Claims. (Cl. 63—2)

The present invention relates generally to the jewelry art, and is more particularly concerned with the provision of a novel and improved hair ornament.

A primary object of my invention is the provision of a hair ornament which may be easily attached and detached with respect to the wearer's hair.

Another object of my invention is the provision of a hair ornament which provides a novel and unique ornamental appearance.

A further object of my invention is the provision of a hair ornament wherein a coil spring is utilized for gripping the wearer's hair.

Another object of my invention is the provision of a hair ornament that has few moving parts and hence is relatively simple and inexpensive to manufacture.

Other objects, features and advantages of the invention will become apparent as the description thereof proceeds when considered in connection with the accompanying illustrative drawings.

In the drawings which illustrate the best mode presently contemplated for carrying out the present invention:

FIG. 1 is a front elevational view showing a hair ornament constructed in accordance with my invention in use;

FIG. 2 is a front elevational view of a hair ornament per se constructed in accordance with my invention;

FIG. 3 is an enlarged rear elevational view thereof;

FIG. 4 is an enlarged top edge view thereof;

FIG. 5 is an enlarged top edge view thereof showing the hair ornament in an intermediate position during attachment thereof to the wearer's hair;

FIG. 6 is a rear perspective view of one of the plates per se that form a part of my hair ornament;

FIG. 7 is a detailed perspective view of the spring gripping member used in my invention;

FIG. 8 is a fragmentary front elevational view, with portions broken away, of a slightly modified form of my invention;

FIG. 9 is a fragmentary rear elevational view thereof;

FIG. 10 is a section taken on line 10—10 in FIG. 9; and

FIG. 11 is a fragmentary perspective view illustrating the spring gripping means utilized in the modified form of my invention.

Although hair ornaments in general are notoriously old, the usual barrette or the like has traditionally employed a clamping arm of some sort for maintaining the ornament in attachment with the wearer's hair. Such an arrangement has generally proven satisfactory, even though the wearer may sometimes experience some difficulty in attaching and detaching the ornament. Where it is desired, however, to mount a hair ornament in the general area of the hair line just above the wearer's forehead, it has been found that the traditional type of barrette is difficult and impractical to use. Thus, there is provided in accordance with my invention a novel hair ornament which does not comprise any clamping arms or the like and which may be easily and quickly attached to the wearer's hair at whatever location is desired, including the general area of the hair line just above the wearer's forehead.

Referring now to the drawings, there is shown generally at 10 a hair ornament embodying my invention. As will be seen most clearly in FIGS. 1 and 2, the ornament

2

10 comprises a pair of similar plate members 12, each having a front surface 14 to which any suitable ornamentation may be applied, and a rear surface 16. It will be understood that each of the plates 12 may be of any desired configuration, although it is important to note that when in use, the plates 12 are in abutting relation with each other, as at the edges 18.

As will be seen most clearly in FIGS. 3 through 5, the plates 12 are resiliently secured to each other by means of a coil spring 20 which extends from the rear surface of one plate to the rear surface of the other. The coil spring 20 may be secured to the rear surfaces of the plates 12 by any suitable means, although I prefer to effect this securing by reversely bending the plates 12 at their abutting edges 18 so as to provide rearwardly disposed reversely bent tab portions 22, each of which carries an integral eye portion 24. Secured to the eye portion 24, as by a rivet 26, is a gripping member 28 (FIG. 7), which gripping member comprises an eye portion 30, a flat base portion 32, serrated gripping lugs 34 extending outwardly from opposite edges of base 32, and an integral upstanding end lug 36, also extending outwardly from base portion 32. It will be understood that rivet 26 functions to assemble the gripping member 28 to the reversely bent tab 22 of each plate member 12, note FIG. 4. Once the gripping members 28 have been assembled in this manner, spring 20 is positioned so that it extends from one end lug 36 to the other, and then the opposed serrated lugs 34 are clenched inwardly so as to grip opposite ends 30 of the spring, as most clearly illustrated in FIG. 3. It will now be seen that the plate members 12 are resiliently assembled to each other by means of the interconnection which is effected by spring 20, and it is important to note that when the plates 12 are in their abutting, substantially uniplanar relationship, as illustrated in FIGS. 3 and 4, the spring 20 is relaxed, and adjacent convolutions of the spring are in abutting relation with each other.

When it is desired to attach the ornament 10 to the hair of the wearer, such as, for example, at the location illustrated in FIG. 1, the plate members 12 are pivoted with respect to each other at their abutting edges 18 so as to assume the position illustrated in FIG. 5. In such a position, it will be seen that the spring 20 has been expanded so that adjacent convolutions are now in spaced relationship with respect to each other. With the ornament in this position, engagement is made with the hair of the wearer so that the hair strands are free to enter into the spaces between adjacent convolutions of the spring. The wearer then folds back the plates 12 so that they once again assume the position illustrated in FIGS. 3 and 4. As this happens, the spring 20 is allowed to resume its relaxed state, whereupon as the adjacent convolutions of the spring once again engage each other, the hair strands located therebetween are resiliently gripped. The hair ornament is then securely maintained in position by this gripping engagement, as illustrated in FIG. 1. When it is desired to remove the hair ornament, it is simply necessary to once again manipulate the adjacent plates 12 to the position illustrated in FIG. 5, whereupon the spring convolutions become spaced from each other so as to release the hair strands located therebetween.

Referring now to FIGS. 8 through 11, a slightly modified form of my invention is illustrated, although it will be apparent that this form of my invention is identical in principle and operation to the embodiment illustrated in FIGS. 1 through 7. Specifically, the modified form of my invention, as illustrated in FIGS. 8 through 11, differs from the preferred form only in the means for securing the spring 20 to the rear of the plate members. Thus, referring to FIGS. 8 and 9, it will be seen that plate member 38 is provided with a plurality of integral prongs 40 for securing an ornamental stone or the like 42 to the

front surface of the plate member. Since the ornamental stone 42 covers the plate member, it is now possible to integrally strike gripping lugs 44 from plate member 38 since the openings 46 which result from this technique are effectively covered and hence do not detract from the appearance of the completed ornament. It will be noted that the lugs 44 are serrated in the same manner as the above described lugs 34 in order to facilitate better gripping engagement with the coil spring, which is shown at 48 in FIGS. 8 and 9. It will be understood that in the form of my invention illustrated in FIGS. 1 through 7 it is not possible to integrally strike the gripping lugs from the plate members since the ornamentation on the front surface of the plate members is in the form of an engraved design or the like, whereupon the openings which result from integrally striking the gripping lugs would be visible from the front of the device, thereby detracting from its ornamental appearance. In use and operation, however, the form of my invention illustrated in FIGS. 8 through 11 is identical to the preferred embodiment illustrated in FIGS. 1 through 7.

While there is shown and described herein certain specific structure embodying the invention, it will be manifest to those skilled in the art that various modifications and rearrangements of the parts may be made without departing from the spirit and scope of the underlying inventive concept and that the same is not limited to the particular forms herein shown and described except insofar as indicated by the scope of the appended claims.

What is claimed is:

1. In a hair ornament, a first plate member, a second plate member located in edge-to-edge abutting relation with respect to said first plate member and being normally in substantially the same plane therewith, a coil spring, means connecting said members and said coil spring, said coil spring having its longitudinal axis extending from one plate member to the other in overlying and generally parallel relation when said plate members are in their normal edge-to-edge abutting relation, the adjacent convolutions of said spring being located in mutually abutting relation when said spring is in the normal relaxed position thereof, said plate members being movable relative to each other, the abutting edges defining a pivot axis therefor, said coil spring having means including exposed ones of said convolutions whereby, upon movement of said plate members causing said coil spring to be tensioned, the adjacent convolutions thereof are separated to define spaces into which strands of hair of the wearer are inserted, said spring capturing the strands of hair between the adjacent convolutions when the plate members are released for return to their normal position.

2. The ornament of claim 1 further characterized in that said plate members are provided with ornamentation on their front surfaces.

3. The ornament of claim 1 further characterized in that said connecting means are lugs integrally struck from said plate members.

4. The ornament of claim 1 further characterized in that said connecting means comprise integral portions of said plate members reversely bent so as to lie adjacent the rear surfaces of said plate members, and gripping lugs carried by said reversely bent portions.

5. The ornament of claim 4 further characterized in that said reversely bent portions are located at the abutting edges of said plate members.

6. In a hair ornament, a first member, a second member located in edge-to-edge abutting relation with respect to said first member, a coil spring interconnecting said members and secured to the rear surfaces thereof in generally parallel relation with respect thereto when said members and coil spring are in the normal positions thereof, the adjacent convolutions of said coil spring being located in mutually abutting relation when said members and coil spring are in their normal positions, said coil spring having means including exposed ones of said convolutions whereby, upon said members being moved relative to each other to tension said coil spring and to cause the adjacent convolutions of said coil spring to separate to define spaces therebetween, the hair of the wearer can be received within said spaces and can be locked between said adjacent convolutions when said members and coil spring are returned to the normal positions thereof, wherein in said ornament is secured in place in the wearer's hair.
